UNITED STATES PATENT OFFICE.

BENJAMIN F. MAYO, OF SALEM, MASSACHUSETTS, ASSIGNOR TO UNITED SHOE MACHINERY COMPANY, OF PATERSON, NEW JERSEY, A CORPORATION OF NEW JERSEY.

LEVELING-MACHINE.

1,104,206.

Specification of Letters Patent.

Patented July 21, 1914.

Application filed June 15, 1911. Serial No. 633,221.

To all whom it may concern:

Be it known that I, BENJAMIN F. MAYO, a citizen of the United States, residing at Salem, in the county of Essex and State of Massachusetts, have invented certain new and useful Improvements in Leveling-Machines; and I do hereby declare the following to be a full, clear, and exact description of the invention, such as will enable others skilled in the art to which it appertains to make and use the same.

The present invention relates to sole leveling machines, and more particularly to that class of sole leveling machines which comprises a leveling device and a shoe supporting jack relatively movable to change the relative longitudinal position of the leveling device and jack.

In the manufacture of turn shoes, it is customary to bend down the margin of the sole in certain types of shoes in order that the sole may conform closely to the curvature of the last and enable the upper to be drawn tightly to the wood in the subsequent lasting operation. After the shoe has been sewed, turned and relasted, it is then subjected to the final leveling operation and great difficulty has been experienced heretofore in devising a leveling machine which would completely remove and obliterate the ridge formed by the upstanding margin of the sole, and it is necessary in the better grades of shoes to supplement the operation of the machine with a hand leveling operation in order to impart the desired finish to the shoe bottom.

The object of the present invention is to provide an improved leveling machine of the class described which is simple in construction and efficient in operation and which will impart the desired finish to the highest grade of shoes without the necessity of a subsequent hand operation.

With this object in view, one feature of the invention contemplates the provision of a positively driven leveling roll which may be manipulated to assume any desired inclination with relation to the line of travel of the shoe.

50 A further feature of the invention consists in the combination with means for varying the relative longitudinal position and lateral inclination of the leveling roll and jack, of means for varying the inclination of the leveling roll relatively to the line

of travel of the shoe as the relative lateral inclination of the leveling roll and jack is varied. Broadly considered, this feature of the invention is not limited to the employment of a leveling roll in combination with a shoe supporting jack, but contemplates the provision, if so desired, of any suitable leveling device.

Still further features of the invention comprise certain novel features of construction, combinations and arrangements of parts hereinafter described and claimed, the advantages of which will be apparent to those skilled in the art from the following description.

The several features of the present invention will be clearly understood from an inspection of the accompanying drawings, in which:—

Figure 1 represents a side elevation of a sole leveling machine embodying the several features of the invention in their preferred form; Fig. 2 is a detail showing the roll supporting arm and the mechanism for inclining the roll supported thereon; Fig. 3 is a plan view of the structure shown in Fig. 2; Fig. 4 is a section upon the line 4—4 of Fig. 3, looking in the direction of the arrows, and illustrating a portion of the mechanism for driving the roll; Fig. 5 is a section upon the line 5—5 of Fig. 3, looking in the direction of the arrow, and illustrating a detail of the pressure regulating mechanism for the leveling roll; Fig. 6 is a section upon the line 6—6 of Fig. 3 and illustrating a detail of the operating mechanism for moving the roll into an inclined position; Fig. 7 is a detail showing a plan view of a portion of the operating mechanism for inclining the roll; Fig. 8 is a section upon the line 8—8 of Fig. 7, looking in the direction of the arrow; and Fig. 9 is a section upon the line 9—9 of Fig. 7, looking in the direction of the arrows.

Certain parts of the machine are similar in their construction and mode of operation to the machine shown and described in the patent to Eppler, No. 1,004,155, dated September 26, 1911, and will be only briefly described herein in consequence thereof. The sole leveling roll is indicated at 1 and is journaled in the forward end of a frame 2 which is pivotally mounted at its rear end in the upper rear portion of the machine frame 3. The shoe is supported upon a suitable

2
 jack 4 which is pivotally mounted at 5 on the jack carrying frame 6. The shoe supporting jack 4 is rocked laterally by the operator and at the same time is moved back and forth beneath the leveling roll to effect a relative longitudinal movement of the leveling roll and shoe sole. To this end, the jack carrying frame 6 is pivotally mounted in the machine frame at 7 and is oscillated by a connecting rod 8 and a crank 9. To effect the lateral movement of the jack, a handle 25, as shown clearly in Fig. 1, is secured to the jack and projects into a position conveniently accessible to the operator. The crank 9 is mounted upon a crank shaft 10 to which a partial rotation is imparted periodically in opposite directions by a large friction disk 11 engaged alternately by a pair of small friction disks locked to the pulleys 12 and 13 respectively. A rocker frame 14 is pivotally connected to the machine frame at 15 and is operated to throw either of the small friction disks into engagement with the friction disk 11 by a handle 16 conveniently accessible to the operator. A continuous rotation is imparted to the pulleys 12 and 13 from the drive pulley 17 through a belt connection 18. To prevent an overthrow of the jack supporting frame in case the operator does not move the handle 16 at the proper time, an automatic stop mechanism is provided which is indicated at 19. The roll 1 is yieldingly held against the sole of the shoe by a treadle 22 which is connected to the roll supporting frame 2 through a spring 23. The leveling roll is continuously rotated during the operation of the machine by the drive pulley 27 supported in the upper rear portion of the machine frame and operated from the main drive shaft through a suitable belt connection.

In turn shoes having extension edges, after the shoes have been turned and relasted, the margin of the sole stands up obliquely from the main body of the sole forming a ridge and in all turn shoes the line of stitches has a tendency to bulge the outer surface of the sole and form a ridge adjacent to the margin. In order to completely remove and obliterate either one or both of these ridges which may be formed, it is necessary to subject them to a rubbing movement which is directed outwardly toward the margin of the sole. In the present invention, the leveling device is swiveled about a vertical axis in order that any desired inclination may be secured with relation to the line of travel of the shoe, and as the shoe supporting jack is moved longitudinally beneath the leveling device a rubbing action in an oblique direction is imparted to the sole. In the simplest and most efficient form of the invention which has yet been devised, a positively rotated leveling roll is provided

which is driven at a higher speed than the jack. The leveling roll is operatively connected to the shoe supporting jack and upon rocking the jack laterally, the roll is inclined to the line of travel of the shoe. In order to accomplish the above ends, the leveling roll is connected to the drive pulley 27 through a pair of bevel gears 28 and 29 which operatively connect the pulley with a shaft 30 journaled in the frame 2. The shaft 30 carries a bevel gear 31 upon its outer end which engages with the upper face 33 of a double faced bevel gear 32. In order to drive the roll in any angular position, the gear 32 is mounted concentrically with the vertical axis about which the leveling roll 70 swivels. The roll 1 is driven from the gear 32 by a bevel gear 35 engaging with the under face 34 of the gear 32. The roll is carried between the two arms of a yoke-shaped frame 36 which is provided with a stud shaft 37 journaled vertically in the frame 2 and retained in position by a bolt 38. The gear 32 is journaled upon a stud 39 threaded in the frame 36 in vertical alinement with the stud shaft 37. In order to incline the leveling roll as the shoe supporting jack is tipped laterally, suitable connections are provided between the roll and jack. The jack 4 is connected to a shaft 40 through a universal joint 41 so that upon tipping the jack the shaft 40 will be rocked proportionately. The shaft 40 is slidingly supported in a bearing member 43 provided with two downwardly projecting arms 44 and 45 between which a toothed segment 46 is retained. The segment 46 is splined to the shaft 40 in order to rock with the shaft but is retained against longitudinal movement therewith by the downwardly projecting 105 arms 44 and 45.

A transverse shaft 47 is fastened in the frame of the machine and slidingly supports a sleeve 48 upon which the bearing member 43 is journaled, as shown clearly in Fig. 6. 110 The sleeve 48 is provided with a series of teeth 49 upon its under face engaging with the teeth 50 formed upon the toothed segment 46 so that upon an oscillatory movement of the segment, the sleeve 48 will be 115 moved longitudinally upon the shaft 47. A bell crank lever, indicated at 51, has one arm 52 operatively connected to the sleeve 48 in order to rock the bell crank upon a longitudinal movement of the sleeve. As 120 the shoe supporting jack is tipped laterally, the segment 46 will be rocked correspondingly and as the jack is moved back and forth beneath the leveling roll, the bearing member 43 and the toothed segment 46 will 125 be rocked about the shaft 47. As it is only desired to utilize the longitudinal movement of the sleeve 48 imparted by oscillating the toothed segment about the axis of the shaft 40, the sleeve 48 is provided with a slot ex- 130

tending throughout one half the circumference, as shown clearly in Fig. 8 and a short shoe 53 having the same width as the slot is supported upon the end of the arm 52 and is seated in the slot. In order to allow a free longitudinal movement of the sleeve 48 and the shoe 53, the bearing member 43 is cut away as shown clearly in Fig. 7. The rocking movement of the bell crank 51 is communicated to a rod 55 which is connected at one end to the second arm 54 of the bell crank. An arm 56 is pivotally mounted at 57 on the frame of the machine and the opposite end of the rod 55 is connected to the arm 56 midway of its ends. The outer end of the arm 56 is connected to one side of the yoke 36 through a link 58 and an upstanding stud 59 mounted upon the yoke, so that upon rocking the bell crank 51 the yoke 36 is inclined correspondingly.

The operation of the machine is as follows: Assuming that the shoe has been properly jacked, the control lever is then manipulated to start the machine, whereupon the shoe supporting jack is moved slowly forward to bring the toe of the shoe beneath the leveling roll. As the leveling roll engages with the sole and is progressively advanced longitudinally of the sole, the operator tips the jack to incline the shoe laterally of the roll. If the jack is tipped to enable the roll to bear upon the left side of the shoe, the roll, through the connecting mechanism, is inclined to the line of travel of the shoe in such a manner that it exerts an outward rubbing action which is directed toward the margin of the sole and which serves to obliterate the upstanding margin or ridge formed upon the surface of the sole. As the curvature of the edge of the sole varies, the jack may be tipped more or less in order to vary the inclination of the roll and insure that the rubbing action shall always take place in the proper direction at every point upon the sole. When one side of the shoe is properly leveled, the jack is tipped in the opposite direction and the leveling roll is made to assume a corresponding inclination to the line of travel of the shoe in the opposite direction in order to rub out the ridge upon the right side of the sole in the same manner as has previously been done with the left side of the sole. As the roll is driven at a higher speed than the jack, the rubbing action will always take place in the same direction irrespective of the direction in which the jack is moving. When the central portion of the sole is being leveled, the jack and leveling roll have no relative lateral inclination and the leveling roll is supported with its axis at right angles to the line of travel of the shoe in order to rub the sole longitudinally.

From the above it will be obvious that the

leveling roll is automatically actuated to impart an outward rubbing action to each margin of the sole in order to smooth out and finish the same and to impart a longitudinal rubbing action to the central portion 74 of the sole for a like purpose.

While it is preferred to employ the specific construction and arrangement of parts shown and described, it will be understood that this construction and arrangement is 75 not essential except so far as specified in the claims and may be changed or modified without departing from the broader features of the invention.

What is claimed is:—

1. A leveling machine having, in combination, a shoe supporting jack, a positively driven leveling roll arranged to assume any desired inclination with relation to the line of travel of the jack to rub the surface of 85 the sole outwardly toward the margin, and means for varying the relative longitudinal position and lateral inclination of the leveling roll and jack, substantially as described.

2. A leveling machine having, in combination, a shoe supporting jack, a leveling device, means for varying the relative longitudinal position and lateral inclination of the leveling device and jack, and means operated in varying the relative lateral inclination of the leveling device and jack for varying the inclination of the leveling device to the line of travel of the jack as the lateral inclination of the leveling device and jack is varied, substantially as de- 100 scribed.

3. A leveling machine having, in combination, a shoe supporting jack, a leveling device, means for varying the relative longitudinal position and lateral inclination of 105 the leveling device and jack, and means operated in varying the relative lateral inclination of the leveling device and jack for positioning the leveling device to rub the central portion of the sole in a longitudinal 110 direction and each margin of the sole in an outward direction, substantially as described.

4. A leveling machine having, in combination, a shoe supporting jack, a leveling 115 roll swiveled about a vertical axis, means for rotating the roll, and means for varying the relative longitudinal position of the leveling roll and jack, substantially as described.

5. A leveling machine having, in combination, a shoe supporting jack, a leveling roll, means for rotating the roll, connections between the shoe supporting jack and leveling roll for inclining the roll relatively to the line of travel of the shoe as the jack is 125 tipped laterally, and means for varying the relative longitudinal position and lateral inclination of the leveling roll and jack, substantially as described.

6. A leveling machine having, in combi- 130

nation, a shoe supporting jack, a leveling roll swiveled about a vertical axis, a bevel gear, means for continuously rotating the bevel gear, and a second bevel gear locked 5 to the leveling roll and engaging with the first mentioned gear, substantially as described.

7. A leveling machine having, in combination, a shoe supporting jack, a leveling roll swiveled about a vertical axis, a driving pulley, a double faced gear, mechanism operatively connecting the driving pulley and the upper face of the gear, and a second gear locked to the leveling roll and engaging 15 with the lower face of the first mentioned gear whereby the leveling roll may be rotated in any inclined position, substantially as described.

8. A leveling machine having, in combination, a shoe supporting jack, means for oscillating the jack, a yoke, a leveling roll journalized in the yoke, and connections between the shoe supporting jack and yoke arranged to turn the yoke about a vertical 25 axis as the jack is tipped laterally, substantially as described.

9. A leveling machine having, in combination, a shoe supporting jack, means for oscillating the jack, a yoke, a leveling roll 30 journalized in the yoke, a sliding sleeve, a

rack formed upon the sleeve, a toothed segment engaging with the rack, operative connections between the sleeve and the yoke, and connections between the jack and toothed segment for oscillating the segment as the jack is tipped laterally, substantially as described.

10. A leveling machine having, in combination, a shoe supporting jack, means for oscillating the jack, a leveling roll, a sliding sleeve, connections between the sleeve and the roll operating to incline the roll as the sleeve is moved longitudinally, an operating shaft connected to the jack, and operative connections between the shaft and sleeve whereby the sleeve is moved longitudinally when the jack is tipped laterally, substantially as described.

11. A leveling machine having, in combination, a shoe supporting jack, a leveling roll, a gear for driving the roll, mechanism for rotating the gear, connections between the gear and roll, and a roll supporting head movable about an axis concentric with the axis of rotation of the gear, substantially as described.
